Primary Examiner — Wan Laymon*Assistant Examiner* — Mark Booker*(74) Attorney, Agent, or Firm* — Stites & Harbison PLLC; Richard S. Myers, Jr.(57) **CLAIM**

The ornamental design for a hanger and storage unit, as shown and described.

DESCRIPTION

FIG. 1 is a top perspective view of the design of a hanger and storage unit showing the new design;

FIG. 2 is a right side elevation view of the hanger and storage unit shown in FIG. 1 (the left side elevation view of the hanger and storage unit is a mirror image of the view shown in FIG. 2);

FIG. 3 is a front elevation view of the hanger and storage unit shown in FIG. 1;

FIG. 4 is a top plan view of the hanger and storage unit shown in FIG. 1;

FIG. 5 is a rear elevation view of the hanger and storage unit shown in FIG. 1; and,

FIG. 6 is a bottom plan view of the hanger and storage unit shown in FIG. 1.

All broken lines shown in the drawing views are included for the purpose of showing environmental structure or non-claimed elements that form no part of the claimed design.
